UNITED STATES PATENT OFFICE.

BENJAMIN P. HOFFMAN, OF TULSA, OKLAHOMA, ASSIGNOR TO THE PIERCE DEVELOPMENT COMPANY, OF TULSA, OKLAHOMA, A CORPORATION OF OKLAHOMA.

PASSING OR BACK-UP TONGS.

Application filed December 18, 1926. Serial No. 155,618.

In handling pipe and tubing in the oil fields, both when moving the same from place to place or coupling or uncoupling the lengths, a tool is utilized and is generally 5 designated as a passing or back-up tongs.

It is a primary object of this invention to provide a tool of the character aforesaid which may be readily manipulated by one 10 person, under certain conditions, or by two persons, as occasion may require, and which admits of the movable jaw being readily replaceable when worn, the movable handle automatically locking to prevent release of 15 the pipe or like part when the jaws have become worn to necessitate replacement.

The invention consists of a tool of the nature stated embodying a frame provided with a pipe receiving recess which is toothed to positively grip the pipe or like part, a fixed 20 handle at one end of the frame, a movable handle pivoted to the opposite end of the frame, and a pivoted jaw operable by means of the pivoted handle and adapted to become automatically locked when the gripping 25 teeth have been worn to render the efficiency of the tool doubtful.

While the drawings illustrate a preferred embodiment of the invention, it is to be understood that in adapting the means to meet 30 specific needs and requirements the design may be varied and such other changes in the minor details of construction may be resorted to within the scope of the invention as claimed, without departing from the spirit 35 thereof.

For a full understanding of the invention and the merits thereof, reference is to be had to the following description and the drawings hereto attached, in which,

40 Figure 1 is a top plan view of a passing or back-up tongs embodying the invention, parts being broken away.

Figure 2 is a front view of the tool, parts of the handle being broken away.

45 Figure 3 is a fragmentary view showing the pivoted jaw locked after the teeth have become worn.

Figure 4 is a sectional view on the line 4—4 of Figure 1.

50 Corresponding and like parts are referred to in the following description and designated in the several views of the drawings by like reference characters.

55 The tool comprises a frame 1 which may consist of a casting or a forging and this

frame is elongated and provided at one end with a socket 2, in which is secured a handle 3, and the opposite end of the frame is slotted, as indicated at 4, to receive a movable jaw 5 and the pivotal end of a handle 6. 60 The frame 1 is provided intermediate its ends with a work-receiving recess 7 which is toothed, as indicated at 8, so as to bite into the pipe or like part to be gripped.

The movable jaw 5 is toothed, as indicated at 9, and is pivoted at one end within the slot 4, and the toothed portion is adapted to be projected into the recess 7 so as to act jointly with the teeth 8 to grip the pipe or other part received in the recess 7. An 65

70 arm 10 projects outwardly from the pivotal end of the jaw 5 and the inner end of the movable handle is disposed to operate in the space formed between the arm 10 and jaw 5. For convenience a socket 11 is pro- 75

75 vided to receive the handle 6 and, in effect may be considered as a part thereof and is included when reference is made to the handle. The arrangement admits of the part 6 being detached from the socket 11 when re- 80

80 quired for any purpose. The inner end of the handle is eccentric to the pivot 12 and provides a cam 13 which is adapted to ride upon the outer face of the pivoted jaw 5 to move the latter into the work-receiving re- 85

85 cess 7 so as to grip the pipe or other part to be held. A projection 14 is formed upon the rear side of the lever and is adapted to ride upon the arm 10 and withdraw the jaw 5 when it is required to release the pipe or 90

90 other part previously gripped. A recess 15 is formed in the rear side of the lever adjacent the projection 14 and when the jaw 5 has been advanced to the limit of its movement said recess receives a projection 16 at 95

95 the outer end of the jaw, thereby forming a lock to prevent release of the jaw in the accustomed way in the ordinary use of the tool, thereby indicating to the workman that the gripping teeth 8 and 9 have become so 100

100 worn as to necessitate replacement in order to insure the efficiency and positive action of the tool in its continued use. Under this condition the pivoted jaw may be released by removal of its pivot 17 or the pivot 12 of the handle 6, it being understood that these pivots may consist of bolts, as clearly illustrated, or may be of any determinate construction.

The outer or rear face of the pivoted jaw 5 is preferably curved to conform to the out- 110

line of the cam 13 to admit of the latter obtaining an extended bearing thereon. When the outer end of the pivoted handle 6 is moved outwardly from the frame the jaw 5 is drawn into the slot 4, by the projection 14 riding upon the inner face of the arm 10, and when the handle 6 is moved toward the frame the jaw 5 is projected into the work-receiving recess 7 by the cam 13 riding upon the outer or rear face of the jaw, as will be readily appreciated.

Having thus described the invention, I claim:

1. A tool of the character specified comprising a frame having a work receiving recess and a slot at one side of said recess, a jaw pivoted at one end within the slot and having a projection at its outer end, an arm projecting from the pivotal end of the jaw, and a lever pivoted within said slot and operating between the jaw and the arm projecting therefrom, and having a projection to coact with the arm and a recess adjacent said projection to receive the projection at the outer end of the jaw and automatically lock the jaw when projected into the work-receiving recess to the limit of its throw.
2. A tool of the character specified comprising an elongated frame having an intermediate work receiving recess, and a slot in an end portion to one side of the said work receiving recess, a handle fitted to the opposite end of the frame, a jaw pivoted at

one end within the said slot and having its rear side curved and formed with a terminal locking projection, an arm projecting from the pivotal end of the jaw and an operating lever pivoted within the said slot and having its inner end of eccentric formation to provide a cam for projecting the pivoted jaw, said lever operating between the jaw and the arm thereof and having a terminal projection and a recess adjacent said projection to receive the projection of the wall and cooperate therewith to automatically lock the lever and jaw at the limit of the effective throw of the jaw.

3. An oil well passing or back-up tongs comprising an elongated frame provided intermediate its ends with an outwardly opening work-receiving recess, and having a fixed handle projecting longitudinally from one end and formed in its opposite end with a slot, a handle pivoted within the slotted end of the frame and extending in an opposite direction to the fixed handle and formed at its pivotal end with a locking element, and a jaw pivoted within the slotted end of the frame and operable by the pivoted handle and formed with a terminal locking element to coact with the locking element of the pivoted handle to automatically lock it and the jaw when the latter is at the limit of its throw.

In testimony whereof I affix my signature.
BENJAMIN P. HOFFMAN. [L. s.]
